SAFETY POISON-FEEDING DEVICE FOR
ANTS AND THE LIKE

Alex Weil, New York, N. Y.

Application March 5, 1947, Serial No. 732,392

7 Claims. (Cl. 43—121)

1

This invention relates to devices for making accessible to insects, such as ants and the like, poisonous food-lures and the like.

One of the objects of this invention is to provide a simple, inexpensive, and efficient device of the above-mentioned character that will be capable of being handled, used, or installed with safety to human beings, animal pets, and the like. Another object is to provide a safety poison-feeding device of the above-mentioned character that will be non-spillable, easy and simple to refill, and adaptable to a wide variety of shapes or conformations as might be desired to meet various peculiar conditions of use. Another object is to provide a device of the above-mentioned character which will not require any particular skill in placement thereof in strategic locations and yet embodies safety or protective features preventing accidental or intentional access to or contact with its poisonous contents by human beings, animals, and the like. Another object is to provide devices of the above-mentioned character that will be simple and inexpensive to fabricate and to charge or refill with the poisonous or like material or insecticide. Another object is to provide a device of the above-mentioned character and a refill device therefor to insure facility and safety of charging or refilling. Another object is to provide devices of the above-mentioned character that will be simple and inexpensive to package for shipment, display, or sale and with adequate safeguards against access to or contact with the poisonous contents thereof. Another object is, in general, to provide an improved device of the above-mentioned character, and other objects will be in part obvious or in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawing, in which are shown illustratively several possible embodiments of the mechanical features of my invention,

Fig. 1 is a front elevation of a device shown as resting upon a flat surface or the like, as in condition for use;

Figs. 2, 3, and 4 are transverse sectional views as seen along the line 2—2 of Fig. 1, showing in each case one set of safety and access elements employed in my invention, but indicating, respectively, different mechanical features of assembly;

2

Figs. 5 and 6 are front elevations of a device like that of Fig. 1 showing, in fragmentary central longitudinal vertical section, other mechanical features of assembly;

Figs. 7 and 8 are central vertical sectional views of modified embodiments capable, for example, of outdoor use and constructed to coact with soil or the like for support in operative position; and

Fig. 9 is a vertical sectional view, showing the coacting structural relationship between the above devices and a refilling device.

Similar reference characters refer to similar parts throughout the several views of the drawing.

Referring first to Fig. 1, out of any suitable material I provide a completely closed container, generally designated by the reference character C, and illustratively it may be shaped or constructed in any suitable manner to provide interior walls or surfaces W which, in transverse cross-section, are preferably circular and may be of uniform diameter throughout, being closed off at the respective ends of the otherwise tube-like structure by any suitable means or conformation of the material of the container C itself; in axial length the closed container C is of a dimension which is preferably a multiple of the inside diameter of the walls W. Preferably at its midpoint lengthwise, as viewed in Fig. 1, the completely closed container C is provided with a pair of tubular elements 10—11 (see also Fig. 2) which are preferably of circular cross-section and preferably of uniform diameter, being coaxially aligned to be in juxtaposition to each other, conveniently by seating and securing the elements 10—11 in suitable diametrically opposed holes 12 and 13, respectively (Fig. 2), provided in the material of the container C. Any suitable means may be employed to secure and seal the elements in place. If the materials employed are metal throughout, a suitable pressure or force-fit, or even soldering, may be employed; or, if the part that has the holes 12—13 in it is of non-metallic material, such as molded and cured plastics, the tubular elements 10—11 may be force-fitted therein, cemented therein, or inserted and then expanded or spun into fixed position therein; or, if the tubular element and the part that has the holes or both of non-metallic material, the former may be conveniently cemented in place.

Within the space S inside the closed container C there is placed the poisonous material, indicated in Fig. 2 at P, and it may be of any desired or suitable character, being usually liquid

or semi-liquid, and for ants preferably being of a sirupy consistency, embodying sweets such as sugar as well as the lethal or poisonous material. In any case such material has or can develop the characteristic of flow or movement relative to the inside walls of the container C. It is included in the device in an amount such that at whatever angle the device C is placed, even with one of the tubular elements 10-11 at the bottom, the level of the liquid or semi-liquid material P never reaches the inner end of either of the tubular elements 10-11. Thus, as viewed in Fig. 2, the maximum depth of the material P is less than the amount that any of the elements 10-11 project inwardly from the wall W of the container. Should the container C, as viewed in Fig. 1, rest on an inclined surface, with one of the tubular elements 10-11 at the bottom, the material P is still insufficient in amount to reach the inner end of a tubular element, and should the device be completely upended, so that the material P flows to the lowermost end thereof, the spacing of the opposed tubular elements from the bottom end is still such that the new depth of liquid material does not reach any of these elements. The container is thus spill-proof, and in case more than one pair of opposed tubular elements is employed, the additional ones are appropriately dimensioned and located relative to the container to maintain the just-described non-spilling relationships for whatever position the structure might be in.

The device may thus be packaged and shipped already charged with flowable poisonous material. When placed in location where ants or like insects are objectionable, these non-spill features make the locating or positioning of the device entirely safe and thus strategic locations may be selected without material risk of contaminating the surroundings or of endangering unwarranted handling of the device or of endangering household pets, etc. Furthermore, probing for the contents of the device by a child is well guarded against, for the only openings are thus provided by the pair or pairs of opposed tubular elements and the insertion of a probe or an instrument into the outer opening of any one tubular element results in guiding the probe or instrument directly into or through the opposed tubular element, without picking up any of the poisonous material. As indicated in the drawing, the spacing between the inner ends of opposed tubular elements is preferably such in relation to the length and cross-sectional area of the tubular element that the inner end of one element is not bypassed by a relatively thin instrument inserted angularly through the other tubular element.

For charging the device with poisonous liquid material, I provide a nozzle-like element N, shown in Fig. 9, this element being tubular and small enough to pass through one of the tubular elements, and which has a passageway 14 that extends from its right-hand end toward the discharge end where the passageway 11 terminates in a lateral branch or discharge vent 15. At the right-hand end the nozzle N is provided with suitable means, indicated at 16, to limit its entry into the selected tubular element, such as element 11 of the device, to such an extent that the lateral discharge vent 15 just reaches beyond the selected tubular element 11 but cannot reach the opposed tubular element 10. Accordingly, the discharge of the poisonous material from the charging element N cannot be directed into the opposed tubular element and, instead, is directed clear of both of

the opposed tubular elements and into the interior of the container or device. Conveniently the part N may be constructed as part of a suitable dispensing container, indicated at 17 in Fig. 9, which can conveniently be in the form of a collapsible metal tube, of which the part 16 is an end wall and with which the part N may be integrally constructed. By squeezing the collapsible tube 17, its contents, which can be in an amount to achieve the above-described non-spilling action in relation to the dimensions of the other parts, can thus be injected, without risk of contamination in handling the dispensing container, into the device.

While the container C can be molded of one piece of plastic or formed of a one-piece metal casting, or of two molded halves cemented or soldered together it is also possible to assemble the container in other ways. In the preferred embodiment shown in Figures 1 and 2 the tubular part of the container is provided with integral annular rings and flanges 18, 19 and 20. Middle flange 18 is preferably polygonal on its external surfaces to provide a series of faces 21 in some or all of which tubular elements such as 10 and 11 are mounted. End flanges 19 and 20 are also of polygonal section so as to be provided with faces 22. This enables the container to be placed on a sloping or flat surface without rolling. Flanges 19 and 20 are preferably larger than flange 18 so that when the container rests on a flat surface flange 18 will be held spaced from the surface to permit access to tubes 10 and 11 in case one of them happens to be in the lowermost position. This permits ants or other insects to enter the tubes to reach the poison.

Flanges 18, 19 and 20 may be molded integrally with container C as shown in Figures 1 and 2 or applied to the tubular portion of the container as separate elements as shown in Figures 3, 4, and 5. According to Figure 3 ring element 23, corresponding to central flange 18 of Figure 1, is slipped over tubular part 24 of the container. Ring 23 and tube 24 are provided with registering openings into which tubes 10 and 11 are pressed to lock the members together.

In the embodiment shown in Figure 4 the container C is formed of a tubular section 25 which has holes for four feeder tubes 10, 11 in its middle portion. Outer ring 26, provided with four registering holes, is placed over tube 25 and two pairs of tubes 10 and 11 inserted to lock the assembly together. In the sectional view of Figure 4, end flange 19 is shown behind flange 26 to indicate the relative size which permits tubes 10, 11 to be held off the ground or floor.

Figure 5 shows another embodiment in which the two end halves of the container comprise cup-like elements 28 and 29 having end flanges 30 and 31 either integrally formed thereon or attached thereto. Middle ring section 32 is provided with oppositely disposed annular seats 33 in which the rims of cups 28 and 29 are cemented to complete the container.

According to the embodiment illustrated in Figure 6 one of the cup-like ends 34 of the container is provided with an integral central flange or ring section 35 and an annular seating recess 36 in which the flange of the opposite cup-like element 37 is received and cemented. This figure also illustrates a modified form of feeder tubes 38 and 39. These tubes are externally flared at their inner ends so that if the syrup or liquid inside the container runs down the inner wall of the container and out along the tubes it will be

guided away from the passageways leading to the outside and will drip back into the container from the lips provided by the flared ends of the tubes.

Figure 7 illustrates a modified embodiment of the device and comprises a container 40 which is ball-like in shape and may preferably be substantially spherical, or at least rounded. This container may be formed of two halves molded of plastic and cemented together or cast or pressed of metal and soldered together along a central vertical plane indicated by the reference numeral 41 in the drawing. Pairs of feeder tubes 10 and 11 are force-fitted, cemented or soldered into the sides of container 40 so as to extend horizontally, although it is not necessary in all cases that axes of the pairs of tubes be horizontal. One or more pairs of tubes 10 and 11 may be provided. Figure 7 shows one pair in section and the inner end of a tube 10 of another pair. As many pairs of tubes may be provided as can be conveniently accommodated by the container. The outer surface of the container is provided with a projection or boss 42 having a threaded recess therein in which is screwed a pin 43 to permit mounting the device in earth, sod or other soft surfaces. During shipment pin 43 may be slipped into one of the pairs of tubes 10 and 11 of the container and screw caps or plugs placed in the outer ends of the tubes to seal the container and hold the pin protected and concealed for shipment. The outer ends of tubes 10, 11 are threaded at 44 to receive screw caps.

It is obvious that flaring feeder tubes 38 and 39 can be used in the modification of Figure 7 as well as the other forms of the device illustrated. Likewise while flaring tubes 38 and 39 are each shown formed of a single piece of material molded in flaring shape it is possible to use a straight metal tube and either enlarge the end to form a flange or secure a separate flange element to a straight tube of metal or plastic.

Figure 8 shows a further modification of the device which comprises a cigar-shaped or fountain-pen shaped container 45 molded of plastic or metal. This may conveniently be formed of two identical molded halves which are cemented together along a longitudinal central plane 46 indicated by dotted lines in Figure 8. Feeder tube portions 47 and 48 may be molded integrally with the halves of the container. Likewise an external central flange 49 may be integrally molded in the parts, this flange having a non-circular cross section, such as a hexagonal section to prevent the device from rolling if it is laid on a flat or sloping surface. Moreover, flange 49 may preferably have a central hollow or annular channel 50 in the region where the holes of feeder tubes 47 and 48 come to the outer surface of the container. Thus also the annular channel 50 subdivides the hexagonal flange 49 into two axially-spaced hexagonal flanges intermediate of which are the apertures from which the tube portions 47 and 48 extend inwardly. Thus the openings of feeder tubes will remain accessible when the device is resting on a flat surface. The device may be shipped already charged with poisonous liquid or syrup 51 therein and the passages of feeder tubes 47 and 48 closed with a pair of thumb-screws 52 threaded into the holes. Thumb-screws are removed when the device is put into operation. This modification of the invention provides a very convenient form of the device for mounting both in the earth and inside of buildings. When mounted in earth or

sod 53, as shown in Figure 8, one end of the cigar-shaped container is merely forced into the soil to a depth sufficient to hold it in place but not deep enough to cover the openings of feeder tubes 47 and 48. This permits the ants or other insects to reach the feeder tubes and enter the container. If the device is used in a building it may be simply laid on the floor or on a shelf where, due to non-circular flange 49 it will stay in position and will not roll.

Any poisonous substance having means embodied in it to attract ants or the insects for which the device is intended may be used inside the container, such as a mixture of arsenic and sugar syrup or thallium sulphate and syrup or various other suitable mixtures. It will be seen that an efficient and substantially foolproof ant and insect poisoning device has been provided which is neat and compact in appearance, made of relatively few parts and which retains the poison in a position readily accessible to insects but practically inaccessible to children or casual explorers without practical destruction of the device. The device is adaptable to mounting in either house, greenhouse or in the field or golf links and can be conveniently charged and recharged with poison at will.

The preferred forms of the device illustrated in the drawing are characterized by continuously concavely rounded inner surfaces and by the absence of corners or disconformities from which the flowable poisonous filling material could drip or splash in such a manner as to travel out of the container through the feeder tubes. The bases of the feeder tubes are disposed in the hollow of the concave surface so that if the container is tilted thereby causing the mass of flowable material, paste, syrup, or the like to flow around the base of a tube its easiest course is to cling to and follow the curved wall rather than travel out the tubes toward their inner-end openings. The tubes themselves are arranged in pairs in such opposed relation that removal of poison with a probe is practically impossible. At the same time the tubes are kept to a minimum length and hence the interior is readily accessible to ants or other insects. By providing flat faces or inwardly curved portions on the flanges in which the feeder tubes are mounted the lengths of the feeder tube passages are reduced.

While the present invention, as to its objects and advantages, has been described herein as carried out in specific embodiments thereof, it is not desired to be limited thereby but it is intended to cover the invention broadly within the spirit and scope of the appended claims.

What is claimed is:

1. A poison feeder for ants or the like comprising an elongated tube-like container having closed ends and having externally thereof and spaced from each other in the direction of the axis of said container two projecting flange-like means presenting companion non-circular contact faces for non-rolling engagement with a surface on which the feeder is placed, said tube-like container having a portion intermediate of said two spaced flange-like means that has two openings therein on opposite sides of the axis of said tube-like container and two tubes, one for each opening, extending towards said axis and toward each other, said tubes terminating with their inner ends substantially juxtaposed and separated from each other by a distance so proportioned in relation to the length and cross

sectional area of the tube that the inner end of one tube cannot be by-passed by a relatively thin instrument inserted angularly through the other tube, said container adapted to hold therein a quantity of poison lure of a depth not exceeding the distance from the inner end of a tube to the inner wall of said container and said tubes providing unobstructed entry and exit for ants or the like, said intermediate portion of said container being of an expanse transversely of said axis less than the expanse of said two spaced flange-like means, whereby, should the feeder be positioned with one of said openings lowermost, said flange-like means holds said lowermost opening away from the supporting surface and free from obstruction thereby.

2. A poison feeder as claimed in claim 1 in which said intermediate portion of said tube-like container comprises flange-like means extending about the tube-like container, thereby to increase the wall thickness of the container at said intermediate portion and to give said two tubes stronger support.

3. A poison feeder as claimed in claim 1 in which said closed ends of said tube-like container extend respectively beyond said two spaced flange-like means and are substantially hemispherical in external contour.

4. A poison feeder as claimed in claim 1 in which said closed ends of said tube-like container extend respectively beyond said two spaced flange-like means and terminate in substantially pointed external contours, whereby said device may also be installed with its axis vertical, by thrusting a pointed end into the ground.

5. A poison feeder as claimed in claim 1 in which said tube-like container comprises at least three parts of which said intermediate portion with said openings is one, said three parts having engaging mating portions for aligning them co-axially, and means securing said three parts against axial separation.

6. A poison feeder as claimed in claim 1 in which said tube-like container comprises at least two parts, said intermediate portion being integral with one of said parts and the other part and said intermediate portion having interfitting and mating portions for aligning said two parts co-axially, and means securing the two parts together.

7. A poison feeder for ants or the like comprising a container having therein a poisonous material in a volume less than the interior volume of the container, said container being substantially sealed excepting for spill-preventing passages that furnish free entry and exit for ants or the like, said passages comprising aligned openings in opposed portions of the wall of the container, said openings having tubes extending therefrom and toward each other with their axes substantially aligned with the line of said openings, the inner and outer ends of each tube being internally of substantially the same cross-sectional shape and area thereby to limit the angle which a thin probe inserted through any tube may make with the tube axis and presenting end faces about the inner open ends of the tubes for spaced juxtaposition to each other, with the inner ends of opposed tubes terminating in spaced relation to each other by a distance so related to the dimensions of the tubes that a straight line passed through one tube at any angle, within the restricted range of angles permitted by the aforesaid relation of the cross-sectional area at the inner and outer ends of the tube, cannot bypass the inner end face of the opposed tube, thus preventing access to the poisonous material.
